UNITED STATES PATENT OFFICE.

MERLE P. CHAPLIN, OF WHITE PLAINS, NEW YORK, ASSIGNOR TO WESTERN ELECTRIC COMPANY, INCORPORATED, OF NEW YORK, N. Y., A CORPORATION OF NEW YORK.

PRINTING TELEGRAPHY.

Application filed June 5, 1923. Serial No. 643,591.

This invention relates to printing telegraphy and particularly to a printing telegraph receiving printer of the class commonly referred to as page printers.

An object of the invention is a receiving printer which is compact in form and efficient and reliable in operation and which is inexpensive to manufacture.

In accordance with the preferred form of the invention there is provided a receiving printer having a stationary platen and a type carrying mechanism which is arranged to be moved transversely of the platen, and which is moved to a selecting position by means under the control of a translating mechanism.

The translating mechanism comprises a plurality of rotatably and horizontally extending rods, which are arranged on the arc of a circle about a shaft normally tending to rotate, and which operate pivoted members in accordance with their positions. Each of these rods has one end bent at an angle of approximately 90° whereby the rods, on being rotated with the shaft, are successively brought under the control of a double-acting electromagnet, which is operated in accordance with line current impulses for causing the movement of the rods into one or the other of their operative positions. Following the positioning of the rods, a second shaft carrying fingers corresponding to the number of pivoted members is released for rotation, whereby a linkage arrangement and a cam shifting arrangement is operated through the movement of the fingers as determined by the pivoted members. The linkage arrangement consists of a series of elements, four in number, the construction of which is such that when the elements controlled by the fingers are moved through various distances, the accumulative effect of such movement is being imparted to a vertically extending type wheel shaft. On the upper part of the type wheel shaft and keyed thereto, yet movable vertically, is a type wheel which has the characters arranged in four sections or rings, one above the other, with 16 characters or spaces per section. As the printer is designed to operate on the Baudot or five unit code, by arranging the characters in this fashion, only four of the elements above noted enter into the selection

of any character on the section of the type wheel which is in a printing position, while the fifth element functions through a cam shifting arrangement to select one of two upper sections or one of the two lower sections of the type wheel. Printing is performed by moving the type wheel into engagement with the printing medium through the action of suitable power operated linkage arrangement.

The auxiliary functions, such as carriage return, line feed, shift and unshift are accomplished through the provision of a series of auxiliary power operating members, the selection of which is controlled by mechanism operated through the instrumentality of the operating fingers, previously mentioned.

A better understanding of the invention may be had from the following description, taken in conjunction with the accompanying drawings wherein the preferred form of the invention is illustrated.

In the drawings:

Fig. 1 is a front elevation of the receiving printer in accordance with an embodiment of the invention.

Fig. 2 is a side elevation of the mechanism shown in Fig. 1.

Fig. 3 is a partial plan view of the mechanism of Fig. 1.

Fig. 4 is a lengthwise sectional view taken along the broken line 4—4 of Fig. 2.

Fig. 5 is a cross-sectional view taken along the broken line 5—5 of Fig. 4.

Fig. 6 shows the mechanism of Fig. 5 in its release position.

Fig. 7 is a detail of the translating and selecting mechanism of the printer.

Figs. 8 and 9 show the type wheel in two of its operative positions and the mechanism for shifting the same from either of the positions shown.

Fig. 10 is a detail showing the method of operating the auxiliary operating members for performing the auxiliary selections, such as line feed, shift and unshift.

Fig. 11 is a detail of the mechanism used for selecting the auxiliary selecting members.

Fig. 12 is a perspective of one of the plates forming the mechanism of Fig. 11.

Fig. 13 is a detail of the mechanism for

preventing the operation of the spacing mechanisms upon line feed, shift and unshift, and no selection.

Fig. 14 is a detail showing the two methods of operating the carriage turn mechanism.

Fig. 15 shows the mechanism for advancing and reversing the inking ribbon.

Fig. 16 shows schematically the circuit arrangement which may be utilized.

The system disclosed in the drawings is preferably operated on the Baudot code of various combinations of five selecting units which may consist either of current and no current or positive and negative units or impulses, although other codes could be used without departing from the spirit and scope of the present invention. These impulses arrive from the distant transmitting station (not shown) over a line L (Fig. 16) and pass to ground through the windings of a relay 10. Relay 10 is provided with an armature permanently connected to a grounded source of energy and adapted to engage its front and back contacts for effecting the energization of a release magnet 11 and the coils of a double acting selecting magnet 12.

Referring for the moment to Figs. 2, 4 and 5, the release magnet 11 is shown with its armature 16 normally out of engagement with a spring held release latch 17. This release latch 17 has its free end notched to receive the free end of a pivoted member 18, also provided on its under side with a projection which normally engages a stop arm 21 fixed to a shaft 22. Shaft 22 extends across the back of the machine and has power communicated thereto from a continuously running motor 23 through a slip friction clutch 24. Arranged about the shaft 22 in the arc of a circle are five selecting rods 28, 29, 30, 31 and 32, each of which has one end bent at an angle of approximately 90° and arranged in a suitable support while the other end thereof is fitted in a member 33 fixed to the shaft 22 so as to be capable of movement horizontally but rotatably movable with the shaft 22. Following the energization of the release magnet 11 and the release of the shaft 22 for rotation, each of the selecting rods 28 to 32 is brought into engagement with a beveled extension secured to armature 34 of the electromagnet 12. As this shaft rotates these rods will be moved into one or the other of two operative positions in accordance with the character of the line current impulses, which control the energization of the coils of the electromagnet 12 accordingly. These rods are arranged to be moved to their selecting position consecutively, but are also arranged in their movement to one or the other of these selecting positions to pass on either the left or right hand side of a stationary locking

vane 35 so that they are retained in the position set until subsequently moved due to a change in the character of the impulse which previously effected the positioning thereof.

As shown in Figs. 3, 4 and 7, each of the selecting rods 28 to 32, inclusive, has secured thereto a disc-like member 36, which is engaged by a bifurcated portion of downwardly extending selectable elements designated by the numerals 40, 41, 42, 43 and 44. On the lower end of each of these selectable elements there is formed a bevel-shaped extension which is moved either to the left or right for controlling the corresponding movement of a selecting finger individual thereto. The selecting fingers, there being five in number, are, as shown in Fig. 3, pivotally secured to a shaft 47, which has power communicated thereto from the continuously rotating motor 23 through suitable gears and a positive friction clutch 48. This clutch 48 is similar to the one shown in Patent 1,480,239, issued January 8, 1924. Therefore, only so much of the mechanism as is necessary for a complete understanding of the present invention is shown, and the description thereof will accordingly be brief.

In accordance with the showing of Figs. 5 and 6, there is also arranged on the shaft 22 two cams 49 and 50, which are adapted to engage two arms 51 and 57 secured to shaft 52. One of these arms will engage a projection on cam 50 at the same time that the depression in cam 49 reaches 51. Both arms have rollers in their ends which engage in the surface of the cams and shaft 52 is rocked positively in both directions, and is held fixed in one position during the larger portion of the rotation of shaft 22 with the cams mounted thereon. To rocking shaft 52 is secured a lever 53 having a roller at its end and adapted to engage the slip friction member of the clutch mechanism 48. Just before shaft 22 reaches its stop position and after the rods mounted thereon have been positioned, cams 49 and 50 act upon rocking shaft 52 and lever 53 to release the slip friction member of clutch 48. As described in my patent previously mentioned, following the release of the slip friction clutch member, a metal disc such as 55 is caused to move laterally into engagement with the main friction drive member. Consequently a direct driving connection is effected between the driving motor and the shaft 47.

As shaft 47 is rotated, the operating fingers 60 to 64, inclusive, will be brought into engagement with the selectable elements 40 to 44, whereby the operating fingers will be moved to a selecting position simultaneously. By continued rotation of shaft 47 each of the operating fingers is arranged to move cam members such as 68 to 72, in-

clusive to four of which there is secured an element of the linkage arrangement through which rotary motion of the type wheel is imparted. Each of these members is arranged to occupy either of two operative positions, and accordingly four of these members through a series of levers of different lengths are so arranged as to effect the movement of a common bar 85 through 10 various distances.

Connected to the fifth cam member 68 is a reciprocating bar 82, which together with cams 128 mounted on each end thereof and arranged to operate a lever 118 serves to 15 position the type wheel vertically which is rotated by the linkage arrangement. These cams, through suitable mechanism, will locate the type wheel in one of two possible positions determined by the cam member 20 68. All of the cam members, 68 to 72 inclusive, are connected through bell cranks to corresponding elements of a ball selecting device by means of which the auxiliary functions or stunts are selected, and connection 25 is made to the source of power for their operation.

In accordance with the showing of Figs. 2, 3 and 7, this linkage arrangement comprises levers 80 and 81, the ends of which are connected through links 75, 76, 77 and 78, to cam members 69, 70, 71 and 72, respectively. Levers 80 and 81 are pivoted between the side members of lever 85. Points at which these levers are pivoted are so arranged that 30 the motion of the end of lever 80, which is connected to cam member 71, imparts a motion to the end of lever 85, connected through gear and segment to shaft 88, a distance equal to one unit space. Similarly, the end 35 of lever 80, connected through link to cam 72, moves the end of lever 85, and shaft 88, through a distance equal to 2 units of space. The end of lever 81, connected to cam member 69, moves the end of lever 85, and shaft 88, through 4 units of space. Also the end 40 of lever 81, connected to cam member 70, moves the end of lever 85, and shaft 88, through 8 units of space. It will thus be seen that the various positions of cams 69, 70, 71 and 72, will produce 16 possible positions being derived at the end of lever 85 and shaft 88.

As previously mentioned the end of lever 85 carries a gear segment adapted to engage pinion 87, at the lower end of shaft 88. At the upper end of shaft 88 is a beveled gear 89, which is adapted to engage a second beveled gear 92 mounted on shaft 93. Slidably mounted on shaft 93 is a structure 45 carrying the printing mechanism including the type wheel shown more in detail in Figs. 8 and 9. Included in this mechanism and slidably keyed to shaft 93 is a rocking beveled gear 102, adapted to engage a co-operating rocking beveled gear 101, which

is secured to the type wheel shaft 97. Secured to shaft 97, for rotation therewith, but slidably mounted thereon is a type wheel structure 96, consisting of 4 type wheels A, B, C and D mounted one above the other. 50 Thus it will be seen that the motion of the cams 69, 70, 71 and 72, through the linkage arrangement and gearing previously described will determine the rotative position of the type wheel 96. The endwise or vertical 55 position of the type wheels which determines which of the four wheels will be brought in engagement with the printing ribbon to give an impression on the paper, is determined by two things. First, the selection of one or 60 the other of the two upper wheels or the two lower wheels, is determined by rod 82 with cam members 128 mounted thereon, and second by rocking of shaft 126 with cams 125 65 mounted thereon. The sliding of rod 82 with cams 128, rocks lever 118 about the center of shaft 126 a distance sufficient to move the type wheel a distance equal to that between two adjacent wheels. The rocking of shaft 126 and cams 125 moves lever 118 70 about rod 82 as a pivot a distance sufficient to move the type wheel two wheel spaces. As has been previously described rod 82 is connected to cam member 68; hence the 75 position of this cam member determines a selection between one of the upper or one of the two lower wheels. Shaft 126 with cams 125 is operated by auxiliary or stunt mechanism of which a more complete description will be given later, and the position 80 of this shaft and cam determines whether one of the two lower or one of the two upper wheels will be used for printing. In the machine, as illustrated, the letter or lower case characters will be located upon the two 85 upper wheels, and the figures and other upper case characters on the two lower wheels. It is possible through the linkage arrangement previously described and operated by cams 69, 70, 71 and 72, to select any one of 90 sixteen possible positions whereby characters located on any one of the 2 type wheels may be selected. Also by a combination of movement between the sliding cams 128, operated by cam lever 68, and that of rocking 95 cams 125 operated by the stunt mechanism, any one of the four wheels may be located in printing position. Mechanism is thus provided for selecting 64 possible positions or characters by the rotation and endwise 100 motion of the type wheel.

The type carrying mechanism 100 comprises a frame 106 and 107 adapted to slide endwise on shafts 93 and 91. Mounted between the sides of frame 106 and 107 on pivots 103 and 104 is a swinging member 99 105 in which the type wheel and type wheel shaft are mounted. The type wheel is made in four circular sections, mounted one above the other on sleeve 96. Sleeve 96 is slidably 110

mounted on shaft 97 but is secured against rotary movement. Shaft 97 is mounted in swinging frame 99 by journals at each end. Also secured to shaft 97 is one member of a pair of rocking bevel gears, namely gear 101, and gear 102 which is mounted in frame 107 and slidably keyed to shaft 93. These gears, 101 and 102, have been designated as rocking beveled gears for the reasons that they not only provide a rotary connection between shafts 93 and 97 but also permit of a rocking movement of type wheel carrying member 99 about its pivots 103 and 104. The pivots 103 and 104 are located in line with the meshing point of gears 101 and 102, and the shape of the teeth of these gears is such that at any position gear 101 will rock around a tooth in gear 102 without effecting any jamming condition between the teeth of the two gears, and also without changing the relation of shafts 93 and 97. As will be described hereinafter, the type carriage is moved from left to right step-by-step under the tension of a spring 208 following the printing of each character unless the cut-out mechanism under the control of the auxiliary selecting elements is effective for preventing the spacing action.

Printing of the selected character is effected by moving the type wheel carrying structure 99 with the type wheels located therein from the position shown in Figs. 1 and 2 to that shown in either of Figs. 8 and 9. While the proper character to be printed is being selected by rotating and shifting the type wheel, as has been previously described, the type wheel carrying mechanism 99 is separated from the printing medium or paper, as is shown in Figs. 1 and 2. After the type wheel has been located, auxiliary mechanism connected to power shaft 47 is brought into play to swing the type wheel carrying mechanism 99 about its pivots 103 and 104, and to bring the particular character on the particular wheel selected into engagement with the printing medium and paper, which position is illustrated in Figs. 8 and 9. This auxiliary mechanism for effecting the motion for printing consists of an eccentric 141, which is mounted on shaft 47, and which has connected thereto at the bottom a lever 196, which is used for performing auxiliary functions as are hereinafter described. A second connection or link 135 is secured to eccentric 141 approximately 90° from the point of connection of lever 196. This link 135 connects to a lever 136 secured to shaft 133 at a point beyond the travel of the type carrying frame 107. Also pivoted to shaft 133 is a second lever 132 which is made adjustable for permitting a variation in the printing blow and which is secured to link 137. Link 137 is connected to shaft 91 by means of a lever 134. In the type carrying frame 107, slid-

ably keyed to shaft 91, is lever 138, which is in turn connected through link 139 to lever 140. There is also mounted on pivots 103 and 104 a locking lever 142, which is connected to lever 140 by spring 146. Suitable means is provided to effect a definite minimum angular spacing between levers 140 and 142 so that spring 146 will always be under a definite tension. It is to be noted, however, that the eccentric 141 is effective for operating the linkage arrangement just described following the positioning of the type wheel in a printing position.

As is true in standard typewriter practice the inking ribbon passes around the fingers of a member carried by the type wheel carriage, the space between such fingers being wide enough to permit the movement of the type wheels between them. Thus the ribbon after each printing operation moves back with the type wheel carriage giving full visibility of the printed characters.

In order that the selected type will be correctly aligned, mechanism is provided for not only aligning the type wheel in a horizontal plane, but also aligning the type wheel in a vertical plane. This mechanism comprises, Figs. 2, 8 and 9, a vertically extending member 142, which has secured at its free end a pair of fingers 143, while at a point intermediate its ends there is secured a knife-like member 144. On the lower end of the member 142 there is secured an extension 145 which normally tends to move under the action of a helical spring, but which is restrained due to the engagement of one end of the extension with a projection on the connecting member 140 through which the type carriage is rotated. Thus, when the eccentric 141 moves the connecting links for causing the rotation of the type wheel carriage, the projection on the connecting member 140 is moved and carries with it the free end of extension 145 so that this extension, together with the vertically extending member 142 is moved toward the type wheel. As these elements are moved from their normal position, the fingers 143 assume a position on the upper and lower sides of the aligned section of the type wheel for aligning the type wheel vertically. At the same time, the member 144 engages the teeth of a toothed wheel 147 carried by the shaft 97. Accordingly, any slight displacement of the type wheel will be corrected. This latter feature is clearly shown in Figs. 8 and 9.

The first function of this lever is through its locking levers 144 and 143 to accurately locate in both rotary and vertical directions the type wheel in the positions selected. As soon as the locking members on lever 142 have seated themselves on the type wheel and locking wheel 147 of the type wheel

carrier mechanism 99, lever 142 becomes fixed with relation to the carrier 99 and both begin motion together about pivots 103 and 104. Spring 146 provides a yielding connection between levers 140 and 142 at this point so that the type carrying mechanism 99 will be given an easy and gradual start on its printing motion, and the locking members of 142 will always be held in engagement with the locking wheel and type wheel. Due to the arrangement of the eccentric linkage connecting lever 140 to shaft 47, the motion is rapidly accelerated so that by the time the type wheel carrier mechanism 99 reaches the position shown in Figs. 8 and 9 it will have acquired considerable momentum, and the printing through ink ribbon or other printing medium on the paper on roll 150 will be by impact similar to that applied on a type bar printer, or the ordinary type bar typewriter. After the type wheel has come in contact with the paper and printed the selected character thereon the linkage arrangement moves back to normal position, carrying with it the type wheel carrying mechanism 99 to the position shown in Figs. 1 and 2 against stop 98. Lever 142 then continues its motion so as to move the aligning members 143 and 144 to again permit the rotation of the type wheel shaft.

Positioned in front of the type wheel is a platen 150 mounted on a shaft 151, which is journaled in a pair of uprights 152 and 153, and which is capable of being rotated through the action of a pawl and ratchet mechanism for moving the paper. The paper 154 is wound on a roll 155 having extensions loosely fitted in bifurcated portions of supporting members such as 156 (Fig. 2). The paper 154 is arranged to pass between a guide 157, rollers 158 and the surface of the platen 150, as is common practice in connection with typewriters.

As shown in Figs. 1, 8 and 9, positioned just below the lowermost section of the type wheel and encircling the shaft 97 is a circular member 110. This circular member 110 is capable of being moved either in an upward or downward direction but does not rotate with the shaft 97 as do the sections of the type wheel. Fastened to the member 110 is one end of an L-shaped member 111, which has its other end fitted with a pair of rollers 112 and 113. Interposed between these rollers 112 and 113 is a shaft 116 which is arranged to be moved by means of two mechanical movements. The mechanism for moving the shaft 116 in this manner comprises a pivoted lever 118, which has in juxtaposition to its pivotal point an aperture in which there is fitted a cam-like member 125. The lever 118 also has an aperture 120 in the end opposite to the one which

is secured to the shaft 116. Inasmuch as the carriage 100 is arranged to be moved along the shaft 116, it is necessary that each end of this shaft to effect the movement of the sections of the type wheel be capable of being moved. Accordingly, at opposite ends of this shaft there are arranged two levers similar to the one described in connection with Figs. 1, 8 and 9. In the central aperture of each of these levers there is arranged cams 125 which are carried at opposite ends of a shaft 126. This shaft 126, as will be more clearly described hereinafter, is rotated upon the selection of one of the auxiliary selecting elements for causing the movement of the shaft 116 a distance sufficient to move the type wheel two section spaces. In order to position the type wheel to any one of its two other positions, there is fitted in the apertures 120 members 128 and 129, which like the cams 125, are secured at opposite ends of rod 82 and serve to move the levers 118 in accordance with the movement of the link 79. Thus, when the link 79 is operated by the distributing and translating mechanism previously described, shaft 82 is moved so that the members 128 and 129 are shifted to engage surfaces of the apertures in each of the levers 118. Consequently the levers 118 are moved about shaft 126 so as to cause a corresponding movement of the shaft 116 and likewise the movement of the type wheel to move either of the two of the sections thereof into printing position.

The auxiliary functions, such as carriage return, line feed, shift and unshift are accomplished in the present invention through the action of an auxiliary translating mechanism. This mechanism is in a number of ways similar to the arrangement disclosed in U. S. Patent 1,545,581, granted July 14, 1925. As described in the patent just referred to, there is arranged in a housing 162 a plurality of plates 163, 164, 165, 166 and 167. Each of these plates is capable of being moved laterally and has arranged on different centers Fig. 12 a plurality of apertures. In each of these apertures there is arranged a spherical member or ball. The balls in adjacent plates, under certain conditions, are brought into alignment with one another in a particular series for forming a rigid operating connection. The means for moving the plates 163 to 167, inclusive, comprises five levers 170, 171, 172, 173 and 174, each of which is individual to one of the connecting links 75, 76, 77, 78 and 79. In other words, these levers will be moved in accordance with the operation of the operating members 50 and 54. On the movement of these operating members in accordance with the operation of the translating mechanism the plate of the auxiliary selector will be

moved for aligning predetermined ones of the spherical members or balls carried thereby.

As shown in Fig. 12 there is arranged above and below the plates a series of horizontally extending members 178, which have on one surface thereof projecting elements 179. Each of these elements is arranged to engage cam surfaces in each of the plates such as 180 for effecting the restoration of the previously selected auxiliary selecting element.

One of the plates forming a part of the housing 162, has two rows of apertures corresponding to the two rows of spherical members or balls and has loosely fitted therein pins 181. Two rows of apertures are provided in order to accommodate, in as small a space as possible, the operating members of the auxiliary selecting elements, and for this reason some have different pivotal points than others. Each of these pins is arranged upon the alignment of the spherical members or balls to which it is individual to condition the auxiliary selecting element individual thereto for operation. For example, when the spherical members 182 are aligned with a fixed spherical member or ball, pin 181 is moved so as to cause the movement of a member 185 pivoted at 183 to which there is secured a connecting link 188, which has its other end secured to hook bar 189. Likewise pivoted to rod 184 are the other of the operating members 35 thus making a very compact structure. To the hook bar 189 is secured a lever 190, which has secured at its other end a vertically extending rod 191 to which there is secured a bell crank 192 (Fig. 2) and to which is secured a pawl 193. Pawl 193 is arranged to engage the teeth of a ratchet wheel 194 rigidly secured to the shaft 151, upon which the platen 150 is rotatably mounted. When the hook bar 189 is moved due to the movement of the pin 181, the projection thereof is moved in the path of a universal bar 196 (Fig. 10), whereby upon the movement of this bar through the action of the eccentric 181 the lever 190 will be rotated for causing the movement of rod 191. Through the movement of the rod 191 and bell crank lever 192, the pawl 193 is moved to a position where it engages the next succeeding tooth in the ratchet wheel 194. Consequently, upon the upward movement of the lever 190, the rod 191 is moved so as to cause the pawl 193 to advance the ratchet wheel 194 a distance equal to one tooth, and accordingly position an unprinted area of the paper or printing medium with respect to the type wheels. The backward movement of the ratchet wheel 194 is restrained by a lever 195, on the fore end of which is secured a roller normally in engagement with the teeth of ratchet wheel 194.

Inasmuch as it is desired to advance the type carrying mechanism following the printing of each character, the mechanism for accomplishing this feature is arranged to be operated upon each operation of the universal bar 196. This mechanism, as is clearly shown in Figs. 1 and 2, comprises a pair of toothed racks 200 and 201, one of which is stationary while the other is movable laterally, and which are positioned just below the type carriage 100. Fixed on the under side of the type carriage 100 are a pair of pawls, one of which engages the teeth in the movable rack 200 while the other engages the teeth in the stationary rack 201. The mechanism for moving the rack 200 and a corresponding movement of the type carriage 100 comprises a bell crank lever 204, which has one end fitted in a bifurcated portion on the edge surface of the rack 200. To the other end of the bell crank 204 is pivoted a lever 205, which is secured to a link 206 fastened to one end of the universal bar 196. A spring connects 204 and 206 in such a manner as to hold 204 and 205 normally in a straight line against a lug on 205. This spring yields under space cut out operation, as will be described later. Thus, upon each operation of the universal bar 196 the link 206 will be pushed upwardly for causing the movement of lever 205 and the rotation of bell crank lever 204 together with the movement of the toothed rack 200. For each full movement of rack 200 the type carriage 100 will be stepped to the right owing to the engagement of the pawl carried by the carriage 100 with the teeth of this rack a distance sufficient to allow the other pawl to engage the next succeeding tooth in the stationary rack 201. Now, upon the restoration of the bell crank lever 204 through the downward movement of the link 206 and lever 205, the rack 200 will be moved to its normal position, but the type carriage 100 will remain in the new position owing to the engagement of the pawl carried thereby with another tooth in the stationary rack 201.

As is common practice in receiving printers wherein the messages are printed in page form, the type carriage is moved from left to right against the tension of a carriage return spring. The carriage return spring in the present instance is designated by the numeral 208, which has one end fastened to the carriage 100 so that for each movement of the carriage greater tension is placed on the carriage return spring 208. When it is desired to return the carriage to its extreme left hand position it is necessary to set the plates 163 to 167 in a manner such that another set of the spherical members or balls are aligned. The alignment of the spherical members in the plates 163 to 167, inclusive, is such that the pin 181 individual

to link 209 is operated to cause the rotation of bell crank lever 210 (Fig. 14), whereby link 209 is moved laterally. Accordingly, the bar 211 is moved directly for effecting the return of the type carriage. One end of the bar 211 is bifurcated and has fitted therein a pin 212 carried by a crank 213. The crank 213 is secured at one end of a rod 214, which also has secured thereto a lever 215. The lever 215 is secured to a member 216, which has secured at opposite ends bell crank levers 217 and 218, these bell crank levers having one arm connected to the member 219 interposed between the racks 200 and 201. When the bar 211 is moved rod 214 will be rotated for imparting to member 216 a horizontal movement, which through the bell cranks 217 and 218 produces an upward movement of the member 219 for causing the disengagement of the pawls in engagement with the teeth in the racks 200 and 201. Inasmuch as the carriage 100 is moved from left to right under the tension of spring 208, the instant the pawls are disengaged from the teeth in the racks 200 and 201, the carriage will be returned to its normal position due to the action of the retractile spring 208. In order to insure the complete restoration of the carriage 100 to its extreme left hand position independently of the movement of the bar 211, a latch 225, having a shoulder for engaging a projection 220 on the bell crank lever 217, is provided. Thus upon the movement of the member 216 to the right, the shoulder on the latch 225 engages the projection 220 on bell crank lever 217 whereby the member 219 is held in its uppermost position for maintaining the pawls out of engagement with the teeth of the racks 200 and 201 until the carriage has been returned to its starting position. The latch 225 is also provided with an upwardly projecting portion 226, which, upon the engagement of the shoulder with the projection 220 on the bell crank lever 217, is moved in the path of the carriage 100. When the carriage 100 has completed its travel, a portion thereof engages the projection 226 for causing the disengagement of the shoulder thereof with projection 220 on the bell crank lever 217, whereby the member 216 is allowed to assume its normal position.

It is often desirable to effect the restoration of the type carriage to its normal position manually and independently of the mechanism which causes this operation in accordance with a predetermined combination of code impulses. In the present case this is accomplished by providing a lever 229, which has one end fastened to the bar 211 while its other end is suitably secured to a crank 230 (Fig. 1). Upon the operation of the crank 230, the bar 211 is moved so that the member 216 is moved laterally for causing the movement of the bell crank levers 217 and 218 in a manner to effect the disengagement of the pawls carried by the type carriage 100 with the teeth in the racks 200 and 201.

As previously described, the type wheel 70 may be moved to position the different rows of characters in a printing position by means of two independently operable mechanisms. One of these mechanisms has already been described, and the other will now be considered. Cams 125, there being two in number, are secured at opposite ends of shaft 126, which is arranged to be rocked whenever the corresponding hook bars thereof are moved so that the projection carried thereby is in the path of the universal bar 196. Each of these cams 125 is fitted in the central aperture of corresponding levers 118 and is arranged so that upon the rocking of the shaft 126, the member 118 will be moved about 75 shaft 82, depending upon which of the cam surfaces of the cam 125 is in engagement. As in the other auxiliary selections, the hook bars for effecting the rocking movement of the shaft 126 are controlled by a series of spherical members or balls arranged in the plates 163 to 167, which are moved to their various positions by the operating members 168 to 172. As shown in Fig. 10, the shaft 126 carries a member 235, 95 which at opposite ends has secured thereto hook bars 236 and 237. The hook bar 236 is arranged to be moved so that the projection thereof is in the path of the universal bar 196 due to the movement of connecting link 238, which is operated by means of one of the pins individual to a series of spherical members or balls in the same manner as described in connection with the operation of the line feed mechanism. Likewise, the hook bar 237 is shifted for moving its projection in the path of the universal bar 196 by the movement of connecting link 239. When either of the projections on the hook bars 236 or 237 is in the path of the universal 100 bar 196, shaft 126 will be rocked due to the movement of member 235 to a position such that cams 125 cause either an upward or downward movement of the member 118 to produce a corresponding movement of the type wheel in accordance with which one of the hook bars is selected. It is to be noted here that the cams 125 effect the shifting of the type wheel from positions A to C, B to D, D to B and C to A, that is, when the cams 125 are effective, the type wheel may be shifted from any of these positions. With the type wheel in these positions, it may be shifted from either the section just above or below by merely causing shaft 82 110 to be moved laterally for causing the engagement of the cam surfaces of members 128 and 129 with the surfaces of the apertures 120 and one of the levers 118. Attached to the lever 235 in the same manner 115

as is hook bar 237 is a second hook bar 228 which through link 227 fastened to the pivoted levers 185 is operated by the spherical members when in space combination.

5 In the operation of the line feed, shift and unshift and carriage return mechanisms and when no selections are received it is desirable to prevent the operation of the spacing mechanism. However, on the other 10 four conditions, when it is desired that the carriage be not spaced, auxiliary means must be provided to accomplish this as is illustrated in detail in Fig. 13. The bell crank 204, which operates the reciprocating 15 rack, is connected to the source of power or lever 196 through a pivoted member 205 and a link 206. The spring connection between lever 204 and link 206 normally holds levers 204 and 205 in a fixed position or a 20 straight line. Connected to lever 204 is an L-shaped member 232. This member 232 is so arranged and located that it is directly above the levers 185, when they are in their operated or selected position. Such of levers 185 as are included in the stunts on 25 which it is desired that the space function be not included, are provided with extensions which come directly under member 232. When one of these stunts is selected, 30 the link 206 will move levers 205 and 204 upward and space the carriage forward. However, when the lever 204 starts to come back to its normal position member 232 attached thereto will encounter the tops of 35 one of the levers 185, which will prevent lever 204 from moving further with link 206, which will continue its motion downward, carrying with it lever 205 and stretching the spring connection between the link 206 40 and lever 204. By arresting the motion of lever 204 the reciprocating rack 200 is not allowed to come back far enough to pick up a second tooth by the pawl on the printing unit. Hence, on the succeeding cycle, when 45 spacing would normally occur, the printing unit will not be spaced for the reason that rack 202 will not be oscillated. Thus, it will be seen on stunt selections where spacing is not desired the carriage is actually 50 spaced forward during the cycle which received and performed the stunt operation but is prevented from spacing during the next succeeding operation.

Another feature of the present invention 55 is the provision of mechanism whereby the line feed mechanism may be operated simultaneously with the carriage return mechanism. The mechanism for performing this function comprises merely an additional hook bar 233, which, upon the selection of the lever 185 individual to the carriage return mechanism causes a hook bar connected to line feed lever 190 to be moved so that its extension or projection lies in the path of 60 the universal bar 196. The provision of the

latter feature enables the return of the carriage and the operation of the line feeding mechanism by the transmission of a single group of impulses. Of course as before these functions may be operated separately 70 and independently.

Interposed between the sections of the type wheel and the paper is an inking ribbon 240, which may be wound on spools 241 and 242. Ribbon spools 241 and 242 are 75 keyed to shafts 243 and 253, respectively, which have secured to their opposite ends beveled gears 244. One of these beveled gears 244 has its teeth meshed with the teeth of a corresponding beveled gear 245, secured at one end of a shaft 246. Intermediate the ends of the shaft 246 is a ratchet wheel 247 arranged to be rotated by a pawl 248 (Fig. 2), operated by a bell crank lever 249 (Fig. 1), and secured to a member 250. Each time the spacing mechanism is operated, member 250 oscillates through a connecting link 251 with each oscillating movement of rack 200 and through connecting levers oscillates pawl 248 and rotates 85 ratchet wheel 247 in one direction which is held by retaining pawl 251. Inasmuch as ratchet wheel 247 is secured to rod 246, a corresponding rotation of beveled gears 245 and 244 is brought about for causing the rotation of ribbon spool 241 and the winding 90 of the inking ribbon 240 on this spool.

Near each end of the inking ribbon 240 is secured a button 252 which is large enough to prevent the inking ribbon, which passes through a bifurcated portion of a rotatable lever 253, from completely unwinding. When the button 252 engages the lever 253, member 254 will be moved to the left. The movement of the member 254 to the left 100 causes the movement of a pair of arms 255 and 256, each of which is provided with shoulders which may be moved in the path of a vertically extending element 257, also secured to the oscillating member 250. As 105 shown in Fig. 15, there is also secured to rod 246 stops 258 and 259, having a surface thereof engaged by the free end of one of the arms 255 and 256. When the member 254 is moved to the left and one of the arms 110 255 is moved so that its shoulder lies in the path of the element 257, the rod 246 will be moved to the left for causing the disengagement of the beveled gears 244 and 245 and the engagement of the beveled gear at the 115 opposite end of shaft 246 with the gear secured to the shaft to which the ribbon spool 242 is secured. The next time the spacing mechanism is operated the oscillating member 250 operates to cause the movement of the stepping pawl 248 in the manner previously described, but owing to the engagement of the beveled gear individual to the ribbon spool 242 with its associated beveled gear, the direction of travel of the inking 120

ribbon 240 will be reversed and the inking ribbon now wound on the latter spool. For holding the reversing mechanism in either of its operative positions there is secured to 5 shaft 246 a member 260 which has two cam like surfaces and which is engaged by a spring held locking member 261.

The operation of the printer mechanism described hereinbefore relative to a particular type selection and the operation incident thereto will now be described.

Assume for the sake of illustration that it is desired to select and print the character P. Further, assume that the character P 15 comprises the following selecting current units; no current, current, current, no current and current. Also assume that the type wheel is in the position shown in Fig. 8, in which position the section D, carrying 20 figures and other special characters, is in a printing position, and that the letter P is carried by section A.

Prior to the transmission of the selecting current units for the selection and the 25 printing of the character P, it is necessary to transmit a series of impulses designated as letter shift impulses. These impulses upon being received over the line L operate line relay 10 for causing the operation of the 30 release magnet 11 and the coils of the double acting selecting magnet 12 and the positioning of the selecting rods 28 to 32, inclusive, to one side or the other of the associated stationary vanes. These selecting 35 rods, being positioned to one or the other of their operative positions, effect the setting of the operating members 68 to 72, inclusive, through the medium of the fingers 60 to 64, inclusive. As previously described, 40 each of the operating members 68 to 72, inclusive, controls one of the plates 163 to 167, inclusive, which have arranged therein spherical members or balls. Upon the positioning of these plates in accordance with 45 the letter shift signal, auxiliary selecting member 238 will be selected for moving the hook bar 236 in the path of the universal bar 196. The universal bar 196 now engaging the hook bar 236 rotates element 235 50 for causing a similar displacement of shaft 126, upon which oppositely disposed cams 125 with respect to levers 118 are formed. The rotation of cams 125 accordingly causes the downward movement of lever 118 and 55 then shifts the type wheel from the section D to the section B, which carries a certain number of the letters of the alphabet, the remaining ones being carried by section A. As previously described, the present invention provides mechanism whereby but four elements enter into the selection of a particular character on one of the sections of the type wheel, while the fifth element serves to select between one of two sections of the type wheel.

Taking up the description now for the selecting and printing of the character P, it being of course understood that prior to the transmission of the selecting current units characteristic of the character P, it 70 is necessary to transmit over the line L an impulse designated as a starting impulse. This impulse in the present case causes the deenergization of line relay 10 and the closure of its back contact, whereby release 75 magnet 11 as well as the right hand coil of electromagnet 12 is energized. It is to be noted here, however, that the energization of the right hand coil of electromagnet 12 has no effect for the reason that the 80 shaft 22 about which the selecting rods 28 to 32, inclusive, are arranged, is now held against rotation due to the engagement of stop arm 21 with the projection on latch 18. The energization of release magnet 11, 85 however, causes an upward movement of release latch 17 through the attraction of its armature 16, whereupon latch 18 by the action of a retractile spring frees the stop arm 21 for rotation. Power being applied 90 to shaft 22, upon which the stop arm 21 is secured, through a slip friction clutch from a continuously rotating motor, shaft 22 will now be rotated. Consequently, the selecting rods 28 to 32, inclusive, will be 95 rotated with shaft 22 and moved consecutively to one side or the other of the stationary locking vane 35 in accordance with the energization of double acting magnet 12. For the first of the selecting current units, 100 line relay 10 will be deenergized for causing the energization of the right hand coil of selecting magnet 12. The armature 34 of selecting magnet 12 will be moved so that the beveled extension carried thereby will 105 lie in the path of the bent end of selecting rod 28. On this operation the selecting rod 28 is brought into engagement with the extenusion on the armature 34 of electromagnet 12, and will be moved to the right, in 110 which position it will remain owing to the passage of the bent end of this rod on the right hand side of the stationary vane 35. The next two selecting current units consisting of current, line relay 10 will be 115 energized, whereby the left hand coil of electromagnet 12 will likewise be energized. For this condition the beveled extension carried by armature 34 of the selecting magnet 12 will be moved to the right so that 120 upon the further rotation of shaft 22 and the engagement of the bent ends of the selecting rods 29 and 30 with the extension carried by armature 34, these rods will be moved to the left. In the case of the next 125 selecting current unit, rod 31 will be moved to the right of the stationary vane 35 in a manner similar to that described in connection with selecting rod 28. Selecting rod 32, like selecting rods 29 and 30, will be 130

- 5 moved to the left of the stationary vane 35. As previously described, each of the selecting rods 28 to 32, inclusive, has individual thereto selectable elements designated by the numerals 40 to 44, inclusive. These selectable elements 40 to 44, inclusive, will be moved consecutively in accordance with the movement of the selecting rods individual thereto.
- 10 Now following the positioning of the selecting rods 28 to 32, inclusive, cam 49, which is also secured to the shaft 22 has its raised portion brought into engagement with lever 57 secured to rod 52. When the raised portion of cam 49 engages lever 57, rod 52 will be rotated a distance sufficient to remove the stop member 53 out of the path of member 54, which forms a part of the clutch 48. As previously described, shaft 52 is rocked positively in both directions and after the release of the stop member 53 it is effective for effecting the operation of shaft 52 to cause the stoppage of clutch 48 after it has completed its cycle of rotation.
- 15 20 25 After the positioning of the selecting rods and just prior to the completion of the cycle of rotation of stop arm 21, this arm 21 engages pivoted member 25 whereupon member 18 is rotated about its pivotal point to bring the projection thereof in the path of stop arm 21 and cause member 17 to again lock it in position.
- 30 35 40 45 The stop member 53 being now out of the path of member 54, the elements of clutch 48 are brought into action and the shaft 47 is rotated by power communicated thereto from the continuously rotating motor 23 through the parts of the clutch 48. Upon the rotation of shaft 47, the operating fingers 60 to 64, inclusive, carried thereby will be moved upon their rotation in accordance with the positions of the selectable elements 40 to 44, inclusive. It is to be noted here that the movement of the operating fingers 60 to 64 is simultaneous. The shaft 47 continues its rotation and causes the operating fingers 60 to 64, inclusive, to pass on one side or the other of the operating members 68 to 72, inclusive, individual thereto in accordance with the positions of the selectable elements 40 to 44, inclusive. Each of the operating members 68 to 72, as is more clearly shown in Figs. 3 and 4, is fan-shaped so that as the operating fingers rotate with shaft 47, the operating member individual thereto will be moved either to the right or left, depending upon the position of the operating fingers.
- 50 55 60 65 Four of the operating members have secured thereto an element of the linkage arrangement, which, through its movement causes a corresponding movement of lever 85 in various distances in accordance with the operation of the links 75, 76, 77 and 78. The movement of these links causes a corre-
- sponding movement of lever 85, which through the engagement of the teeth carried by one end thereof with the teeth of spur gear 87, causes the type wheel to be rotated for bringing the desired character into a printing position. The fifth of the operating members does not enter into the selection of a particular character in a row, but does function to select one of two rows. In accordance with our previous assumption, the character P is carried by a section A and the type wheel is now in a position for printing characters from section B. Operating member 72 for the particular condition chosen being operated, shaft 82 will be moved laterally for causing the movement of members 128 and 129, and accordingly the shifting of the levers 118 for moving the type wheel from section B to section A, upon which the character P is mounted.
- 70 75 80 85 Following the rotation and endwise movement of the type wheel to bring the desired character into a printing position, eccentric 141 through the links 135, 137, and 139 and the bell crank levers 136 and 138 causes the type carriage to be rocked about pivotal points 103 and 104. As previously described this is accomplished by the movement of the projection caused by member 140 out of the path of member 145 whereupon rod 142 under the action of spring 146 is moved forward. In its movement rod 142 causes the correct alignment of the selected type both vertically and horizontally and the further movement of the type carriage to the effect the printing of the selected character. Following the printing operation the eccentric 141 through the connecting levers moves member 140 so that its projection again engages member 145 for returning the type carriage against its stop 98 and the return of the rod 142 to its normal position as shown in Fig. 2.
- 90 95 100 105 As the eccentric 141 is operated, universal bar 196 is likewise operated for causing the operation of the spacing mechanism and the spacing of the type carriage to the right for spacing between characters, as has been previously described in detail. For each operation of the spacing mechanism, as has also been previously described, ratchet wheel 247 will be rotated through the action of pawl 248 for causing the rotation of the ribbon spool, which has the teeth of its beveled gear in engagement with one or the other of the beveled gears carried by shaft 246.
- 110 115 120 Although the invention has been disclosed and described in connection with a particular type of apparatus, it is of course obvious that various departures may be made without departing from the scope and spirit of the invention.
- 125 What is claimed is:
1. In a printing telegraph receiver, a type wheel having the characters arranged there-

- on in several rows, positioning mechanism therefor comprising a plurality of selecting elements, a corresponding number of selectable elements operated thereby, means controlled by certain ones of said selectable elements for determining the row from which the character is to be printed, means controlled by others of said selectable elements for positioning the type wheel to bring the desired character in the particular row selected into a printing position, and means for moving the type wheel to effect the printing of said desired character.
- 15 2. In a printing telegraph receiver, a type wheel having the characters arranged thereon in a plurality of rows, means for selecting a row and a character in the selected row comprising a distributing mechanism controlled by line current impulses, a translating mechanism operated by said distributing mechanism for moving said type wheel to bring the row and character therein into a printing position, and means operated following the selection of the character for moving said type wheel to cause the impression of the selected character on a printing medium.
- 30 3. In a printing telegraph receiver, a type wheel, means for determining the character on said type wheel to be printed comprising distributing mechanism, a series of selectable elements operated successively by the distributing mechanism, operating members having two operative positions and adapted to be moved simultaneously in accordance with the setting of said selectable elements, and means operated by said operating members for positively moving the type wheel to bring the desired character into a printing position.
- 45 4. A self-contained receiving printer and distributor comprising an electromagnetic means responsive to line current impulses, means arranged to be selectively positioned in accordance with the operation of said electromagnetic means, a power shaft, means for releasing said power shaft following the operation of said second recited means, and means carried by said power shaft and operated in accordance with the position assumed by said second mentioned means for selecting and recording a desired character.
- 55 5. A self-contained receiving printer and distributor comprising electromagnetic means responsive to line current impulses, a plurality of selectable elements positioned by said electromagnetic means, a power shaft, means for releasing said power shaft following the positioning of said selectable elements, and means carried by said power shaft and operated in accordance with the positioning of said elements for selecting and recording a desired character.
- 65 6. A receiving printer comprising a type wheel having the characters arranged thereon in a plurality of rows, means for selectively positioning the type wheel to bring the row and the desired character in such row into a printing position, and means operated following the positioning of said type wheel for correctly aligning the type wheel in two directions with respect to a printing medium.
7. A receiving printer comprising a type wheel having the characters arranged thereon in a plurality of rows, means for selectively positioning the type wheel to bring the row and the desired character in such row into a printing position, and means effective after the positioning of the said type wheel for rocking it to cause the printing of the selected character.
8. A receiving printer comprising a type wheel, having the characters arranged thereon in a plurality of rows, means for selectively positioning the type wheel to bring a row and a desired character in such row into a printing position, means effective after the positioning of the said wheels for rocking it to cause the printing of the selected character, and means operated prior to the completion of the printing action to shift said type wheel to correct for any slight displacement thereof.
9. A telegraph receiving printer comprising a type wheel having the characters arranged thereon in a plurality of rows, means for imparting a vertical and rotary motion to said type wheel to bring the desired character into a printing position, and means for moving said type wheel, following the positioning thereof into a printing position to correct for any slight vertical or lateral displacement.
10. A telegraph receiving printer comprising a type wheel having the characters arranged thereon in a plurality of rows, means for imparting a vertical and a rotary motion to said type wheel to bring the desired character into printing position, means for causing the printing of the selected character and means effective prior to the printing action for moving said type wheel both laterally and vertically to correct for any slight displacement.
11. In a printing telegraph receiver, a type wheel having the characters arranged thereon in a plurality of rows, means for selecting the row and character in the row comprising distributing mechanism controlled by line current impulses, a translating mechanism operated by said distributing mechanism for moving said type wheel to bring the row and character in the row in a printing position, and an all mechanical means operated following the selection of the character for causing the movement of said type wheel to effect the impression thereof on a printing medium.

12. A receiving printer comprising a type wheel, positioning mechanism therefor consisting of an electromagnet device responsive to line current impulses, a plurality of selecting elements positioned in accordance with the operation of said electromagnetic device, means operated in accordance with the positions assumed by said selecting elements for determining the character on said

type wheel to be printed, and an all-¹⁶ mechanical connection effective following the positioning of said type wheel to cause its movement and in consequence the impression of the selected character on a printing medium.

15

In witness whereof, I hereunto subscribe my name this 31st day of May A. D., 1923.

MERLE P. CHAPLIN.
